UNITED STATES PATENT OFFICE.

HANS SKREBERG, OF MILAN, MINNESOTA.

BUNDLE-CARRIER CRANE.

1,119,048.

Specification of Letters Patent.

Patented Dec. 1, 1914.

Application filed October 24, 1912. Serial No. 727,627.

To all whom it may concern:

Be it known that I, HANS SKREBERG, a citizen of the United States, residing at Milan, in the county of Chippewa and State of Minnesota, have invented certain new and useful Improvements in Bundle-Carrier Cranes, of which the following is a specification, reference being had therein to the accompanying drawing.

10 My invention relates to improvements in bundle carrier cranes, and the primary object of it is to provide a crane easily and quickly attachable and detachable to harvesters, and particularly to that type of harvester known as the McCormick.

A further object of my invention is to provide a crane which will both better support a bundle carrier and prevent the scattering of the bundle when the main wheel 20 of the binder gets in a dead furrow or low place, and also to have adjustable means for raising or lowering the bundle carrier. This adjustable means relieves the strain on the pivot casting of the bundle carrier, 25 which needs no further description, and also prevents the carrier from partially closing up when the harvester is cutting alongside of corn fields, weeds, etc.

Referring to the drawings—Figure 1 is a 30 perspective view of my improved crane attached to a harvester of the McCormick type. Fig. 2 is a perspective view of my improved crane detached. Fig. 3 is a sectional view taken on the lines 1—1 of Fig. 1.

35 Referring now to the drawings in which like numerals designate similar parts, 1 is a trussed tubular bar, the inner end of which is provided with a flat narrow arm 2, bolted to the inner side of the said tubular 40 bar at 3, by means of a bolt 4, and extending on both sides of the tubular bar at right angles thereto. One end of the arm 2 is bent upwardly at 5 to embrace the under side of the forwardly extending portion of 45 the breast-plate brace-bar of the harvester. The other end of the said arm 2, is bent upwardly at 6, to embrace in like manner the under side of the forked brace 7 of the harvester. The tubular bar 1 extends parallel 50 to the forked brace, above referred to, and rests on the binder frame or casing 8 at a point 9, and thence extends over the bundle carrier terminating at a distance directly above the end of the bundle carrier frame, 55 as is clearly shown in Fig. 1. A hook 10 fitting in an eye 11, which is clamped to the

outer end of the tubular bar 1 by means of a bolt 12, carries a chain 13, which extends downwardly and carries on its extreme end a pin 14. By means of the hook, any link 60 of the chain may be hooked thereon for shortening and lengthening the chain. The said pin 14 is formed of a flat bar of iron having its ends clamped together at 15, and also to the end of the chain by means of a 65 bolt 16, and its other end is outwardly bulged to form an eye 17. The pin is adapted to be inserted within the end of the hollow supporting bar 18 of the bundle carrier after the double finger pivot 19 thereof 70 has been removed and then held firmly therewithin by the insertion of the said double finger pivot 19, through the supporting bar 18, and also through the eye 17 of the pin 14. At the point 9 where the tubular bar 1 rests on the binder frame 8, a bolt 20 passes through the said tubular bar and carries a flat hook 21 on the upper side of the bar 1, a spool 22 or a series of washers, and a brace 23, the ends of which are fastened to the ends of the tubular bar 1, by 75 means of the bolts 4 and 12. The said hook 21 is adapted to hook over the upper side of the forked brace where the said brace is attached to the binder-frame. The brace 23 80 is merely used as a strengthening means for the tubular bar 1.

As will be clearly understood the weight of the bundle carrier will have a tendency to pull down the outer end of the tubular 90 bar and, using the point where the tubular bar rests on the binder frame as a fulcrum, to throw the opposite inner end thereof up, causing the hooks carried by the inner end of the tubular bar to be held firmly in place. 95 The hook which is bolted to the tubular bar at the fulcrum point will keep the tubular bar from sliding sidewise.

Having thus described my invention what I claim and desire to secure by Letters Patent is:

1. The combination with a harvester, of a carrier crane, said crane having a fulcrum point intermediate its ends on the harvester frame, a bundle carrier having one end 105 connected to the harvester and flexible adjustable means carried by the outer end of the said crane and connected to the bundle carrier for supporting the free end of the latter.

2. The combination with a harvester, of a carrier crane, having its inner end pro-

- vided with a hook on each side thereof one hook engaging the under side of the breast-plate supporting bar of the harvester, and the other hook engaging the under side of the forked brace of the harvester, the said crane having a fulcrum point intermediate its ends on the harvester frame a hook carried by the said crane at the fulcrum point engaging the upper face of the said forked brace a bundle carrier having one end connected to the harvester and means carried by the outer end of said crane, and connected to the bundle carrier for supporting the free end of the latter.
3. The combination with a harvester, of a carrier crane, connected to the frame of the harvester, a bundle carrier a flexible

member connected to the outer end of the crane and a pin provided with an eye, said pin carried by the lower end of the said 20 flexible member and passing into the outer end of a supporting bar of the bundle carrier and held therewithin by the insertion of a double finger pivot of the bundle carrier through the eye of the said pin, said 25 pin and pivot forming a connection between the lower end of the flexible member and the bundle carrier for the purpose described.

In testimony whereof I hereunto affix my signature in the presence of two witnesses. 30

HANS SKREBERG.
